JOHN D. TOMPKINS, OF VALATIE, NEW YORK.

PROCESS OF DRYING PAPER.

1,178,556.

Specification of Letters Patent. Patented Apr. 11, 1916.

Application filed May 25, 1908. Serial No. 434,935.

To all whom it may concern:

Be it known that I, JOHN D. TOMPKINS, of Valatie, in the county of Columbia and State of New York, have invented a certain 5 new and useful Improvement in Processes of Drying Paper, and do hereby declare that the following is a full and exact description thereof.

My process relates to the continuous drying of webs of paper.

The process is carried out with very great rapidity, while at the same time the product produced thereby possesses very nearly, if not quite, the same qualities as paper which has been dried by the old slow process of drying at lower temperatures in the presence of atmospheric air. The paper produced is one of very great tensile strength and is free also from any very 10 great internal strains due to uneven drying or shrinking.

My process involves the drying of a traveling web of paper by simultaneously heating both sides thereof. I effect this result by applying to both surfaces of the traveling web of paper effective conductors of heat, apparatus being provided for maintaining said conductors at the proper temperatures to obtain the most effective results.

In general, the moist web of paper is led over the surface of a heated drum and a heated foraminous metal belt is constantly maintained in contact with the other or outer surface of the traveling web during the time that the latter is supported upon the surface of the heated drum. I preferably maintain the drum at a higher temperature than the traveling metal belt. The result of this arrangement is that the web 20 of paper is effectively heated throughout every portion of its body without maintaining any one portion thereof at such a high temperature as will result in charring or weakening the fibers. In the case where the

traveling web is dried upon one heated surface alone, such a surface, in order to attain the speed which I have been able to attain, must be maintained at a very much higher temperature than I use, resulting in damage to the fibers of the web and also in the production of unequal strains throughout the body of the paper due to uneven drying. While the temperatures which I apply to the two surfaces of the paper do not differ markedly from one another, in my process I find it preferable to use a higher tempera-

ture in the drum than I do in the metal belt, for the reason that the moisture in the inner surface of the web of paper, that is to say, the surface which is upon the drum, 60 can only escape by passing through the body of the web itself, while the moisture which is located on the other or outer surface of the web of paper can readily escape through the perforations in the metal belt to the 65 outer air. It will, therefore, be seen that in order to secure an equal evaporation on both surfaces of the traveling web of paper, it would be desirable to maintain the temperature on the inner surface higher than the 70 temperature at the outer surface, so as to produce a greater tendency toward evaporation at the former point than at the latter. Because of the location of a heated belt on the exterior surface of the traveling web, 75 the stratum of air adjacent to the metal belt and therefore adjacent to the web of paper at its outer surface, is heated to a higher temperature than would be the case were the heated metal belt dispensed with. 80 The heating of the layer of air in this way results in lowering its degree of saturation, and consequently, enables it to take up a larger quantity of moisture and more rapidly than would be the case were this 85 stratum of air not heated.

It would seem to be obvious that results of the kind above mentioned could not possibly be obtained by the use of a cold metal belt of any description. Such a belt would 90 not, of course, assist in raising the temperature of the traveling web of paper for the purposes of evaporating the water therein, nor would it produce an outer stratum of air adjacent to the web of paper having a 95 lower degree of saturation than the surrounding atmosphere, nor could these results be obtained by means of a canvas belt or a belt made of any material not adapted to conduct heat effectively, for the reason, 100 that such a belt being a non-conductor of heat, would not assist in raising the temperature of the water in the web, nor in producing a layer of air adjacent to the outer surface of the traveling web of paper having a lower degree of saturation than the surrounding atmosphere. A further very great disadvantage of the latter type of belt is in the fact that it does not permit, 105 to any great degree, the escape of the moisture or water vapor from the web of paper, owing to its impervious nature.

After passing the traveling web of paper between a heating drum and a heated metal belt or apron, the web of paper in my process is separated from the drum and apron so as to permit, as far as possible, the moisture to evaporate and a perfect and equal shrinkage to take place. At this point the metal apron is passed over a heating drum preparatory to being applied again to the surface of the web of paper, to effectively heat the same. After the bulk of water vapor has thus been allowed to escape from the body of the web, the same is again led upon the surface of a succeeding drum where the metal apron is again led into contact with its outer surface to continue the drying process by repeating the steps above described. The web is again separated, the metal apron again pre-heated and the two led upon a succeeding drum in the same manner and to other drums of the same character until the process of drying is entirely completed.

The apparatus which I use in carrying out my process is shown in the accompanying drawings in which—

Figure 1 is a longitudinal vertical section of one type of apparatus that I may use; Fig. 2 is a transverse vertical section of the same apparatus; Fig. 3 is a detail thereof; Fig. 4 is a side elevation of the metal apron used; Fig. 5 is a side elevation of another type of machine which may be used; and Fig. 6 is a plan view of a fragment of the metal apron.

Referring to Figs. 1 to 3, *a* indicates a series of main drying drums carried by the supports *b*, each of which is provided with a means for heating the same such as a steam inlet pipe *b* and a steam exhaust *c*, the former being located at one end of each cylinder, and the latter at the other end. Between and above these cylinders are located a series of auxiliary heating cylinders *d*, having similar steam inlet and exhaust pipes *e* and *f*.

A traveling metal belt or apron *g* is adapted to pass around the auxiliary heating drums *d* and the drying drums *a* alternately. The lower portion of the belt *g* is guided and sustained by a series of idler rolls *h*, which may be heated or not as found desirable. One of these rolls may be made adjustable as shown at *i* in Fig. 1, so as to take up the slack in the belt. For propelling the belt *g* and the main drying drums *a*, a train of gears *j* is provided, every alternate one of which is located upon a shaft of one of the drying drums *a*, and the intermediate remaining ones being located between the gears on the drying drums *a*, so as to propel the latter all in the same direction and at an equal speed. The traveling web of paper *k* is led into the machine, as shown at the right of Fig. 1, over a guide roll *l*, from

which point it passes downwardly between the metal belt and the drying drum at this portion of the machine. The web of paper after passing around this drum passes upwardly out of contact with the apron and drum and is led over a guide roll *m* located at one side of one of the auxiliary heating drums *d*. Symmetrically placed on the other side of this auxiliary heating drum is a similar guide roll *m* for the paper web. The remaining auxiliary heating drums *d*, with the exception of the one located at the back or end of the machine shown at the left of Fig. 1, are each provided with a pair of guide rolls *m*, similar to those already described. The last auxiliary heating roll is provided with a single guide roll *n* similarly located to the guide roll *l*, located at the front of the machine.

Referring to Figs. 4 and 6 which show the construction of the metal belt, I find the most effective arrangement for this portion of my apparatus to consist of a number of curved plates *o* hinged to one another at the points *p* by means of pintles *q* extending throughout the entire width of the metal belt. As shown in Figs. 4 and 6, the method by which I preferably hinge adjacent plates to each other, consists in curving the edges of the plates around the pintles at short intervals throughout the adjacent edge of each plate, one plate being supported from said pinte for a few inches, then the adjoining plate being supported in the same manner for a corresponding distance throughout the entire width of the belt. I have arranged the curvature of each plate so that it will fit closely to the traveling web of paper while it is supported upon the drying drums *a*, so as to obtain the maximum heating effect. I have also arranged the size of the pintles *q* so that while the apron is passing around the heating drums *d*, the central portion of each plate *o* will be in contact with the periphery of the drum, as will also the curved portions of each edge of the plate surrounding the pintles used for hinging one plate to the other. Inasmuch as each plate, therefore, contacts with the heating drum *d* along three different lines, a large quantity of heat can be conducted from the heating drum to the traveling apron. The plates *o* of the apron are provided with a plurality of openings or perforations *r* which may be of any desired shape or size.

The other modification, as shown in Fig. 5, consists of a lower series of drying drums *a'* and an upper series of drying drums *a''*, located intermediate of the members of the lower series of drums. The lower series of drying drums are provided with a series of auxiliary heating drums *d'*, located in the same relation thereto as in the modification shown in Fig. 1. The upper series of drying drums *a''* are provided with a like series

of auxiliary drying drums d^2 , located in an analogous manner, though below instead of above the series of drums. A train of gears j' , similar to the gears j already described, is provided for rotating the lower drying drums a' , and gears j^2 are arranged so as to mesh with these to drive the upper drying drums a^2 through the agency of gears j^3 . Idlers h' , such as those shown in Fig. 1, are also provided for the lower series of drums a' , and similar idlers h^2 are located adjacent to the upper series of drying drums a^2 , but above instead of below the drums. One of the idlers in each set on this machine is made adjustable, as shown at i' and i^2 , so as to take up the slack in each of two aprons g' and g^2 , traveling around the respective sets or series of drying drums. The traveling web of paper in this instance is led into the machine over a guide roll l' , shown at the right of Fig. 5, whence it proceeds around the first member of the lower series of drying drums, thence upwardly over the first member of the other series of drums, and then downwardly again to the next drum in the lower series, and so on until it has passed around all of the drums in the machine. During the passage of the web of paper from one drum to another, each of the traveling belts or aprons g' and g^2 is led around one of the auxiliary heating drums d' and d^2 so as to be pre-heated or reheated preparatory to being led into contact with the outer surface of the traveling web of paper while it is supported upon the drying drums.

In either of the modified forms of the apparatus above described, the moist web of paper is led into the machine between a drying drum and the traveling metal belt, or apron passing over the same, the drying drum being preferably, though not necessarily, maintained at a higher temperature than the temperature of the metal apron while it is in contact with the web of paper supported upon the drum. The web of paper is thus heated from both surfaces simultaneously, so that before it leaves one drum it has become effectively and thoroughly heated throughout its entire thickness. The inner surface of the web, however, that is to say, the surface adjacent to the drying drum, is maintained at a somewhat higher temperature than the outer surface of the web of paper, for the reason that it is much more difficult for the moisture to escape from the body of the paper next to the cylinder than it is from the outer surface of the web of paper, inasmuch as the latter is constantly in contact with the outer air, whereas the moisture in other parts of the body of the web is compelled to pass through the web itself before escaping. The heated metal belt further maintains a stratum of highly heated air in contact with the outer surface of the traveling web of

paper. This stratum of air because of its high temperature, has a lower degree of saturation than has the surrounding atmosphere. Such being the case, the moisture from the web will evaporate much more rapidly and readily than were the air at this point not heated. Again, from the fact that the web is heated from both surfaces simultaneously, it follows that the paper will dry and shrink much more evenly. This is very important, because in the case where the paper is heated from one surface alone, that surface will have a tendency to dry much more rapidly and shrink in a corresponding manner and consequently set up unequal strains throughout the body of the paper, resulting in a product which will have a much greater tendency to tear than in the case where the web is dried evenly.

Provision is made in my process for periodically allowing the web of paper to come in contact with the air freely at both of its surfaces, so as to allow it to dry and shrink to the fullest extent possible and in as even a manner as possible. During these intervals, the portions of the metal aprons are preheated so as to raise them as nearly as possible to their ideal temperature before passing around the drying drums.

While I have described my process above in detail, I do not wish it to be understood that I am necessarily limited to the details herein described, as I consider that many changes might be made without departing from the fundamental principles of my invention. The apparatus by means of which I carry out my process is also capable of many modifications. For example, I might heat the two surfaces of the traveling web of paper by means of any effective conveyer or conductor of heat, which terms I desire to be considered synonymous; that is to say, that I consider any method of effectively heating the two surfaces of the traveling web of paper to come within the purview of my invention.

I claim:

1. The process of drying paper continuously, which comprises supporting throughout a portion of its path a traveling web of paper upon a heated conductor of heat, while bringing into contact with the opposite surface of the web of paper through the same portion of the path a second heated conductor of heat, and then separating the web of paper from both conductors of heat to obtain free lateral shrinkage.

2. The process of drying paper continuously, which comprises supporting throughout a portion of its path a traveling web of paper upon a heated conductor of heat, while applying to the opposite surface of the web of paper through the same portion of the path a second heated conductor of heat, one of said conductors causing the con-

tinual free escape of moisture and then separating the web of paper from both conductors of heat to obtain free lateral shrinkage.

5. 3. The process of drying paper continuously, which comprises supporting throughout a portion of its path a traveling web of paper upon a heated conductor of heat, while applying to the opposite surface of the web 10 of paper through the same portion of the path a second heated conductor of heat, the first conductor being maintained at a higher temperature than the second conductor and then separating the web of paper from both 15 conductors of heat to obtain free lateral shrinkage.

4. The process of drying paper continuously, which comprises supporting throughout a portion of its path a traveling web 20 of paper upon a heated conductor of heat, while applying to the opposite surface of the web of paper through the same portion of the path a second heated conductor of heat, and separating the traveling web of 25 paper from the conductors so as to permit moisture to escape from both surfaces

simultaneously and obtain free lateral shrinkage.

5. The process of drying paper continuously which comprises simultaneously heating 30 both surfaces of a traveling web of paper by means of effective heated conductors of heat which travel in the same direction as and conform to the surfaces of the traveling web of paper, and then separating the web from the conductors of heat 35 to obtain free lateral shrinkage.

6. The process of drying paper continuously which comprises simultaneously heating 40 both surfaces of the traveling web of paper by means of effective heated conductors of heat and then separating the web from the conductors of heat to obtain free lateral shrinkage, the conductor adjacent to one surface causing the continual free 45 escape of moisture.

In testimony that I claim the foregoing I have hereunto set my hand.

JOHN D. TOMPKINS.
